AUTOMATIC FREQUENCY CONTROL

Charles William Earp, London, England, assignor
to International Standard Electric Corpora-
tion, New York, N. Y.

Application July 17, 1942, Serial No. 451,292
In Great Britain July 11, 1941

7 Claims. (CR 250—40)

The present invention relates to oscillator circuit arrangements provided with automatic frequency control.

According to the broadest aspect of the invention, in an oscillator circuit arrangement a controlling voltage is applied thereto to determine the rate of change of the frequency generated, said change of frequency continuing within practical limits so long as said controlling voltage persists.

According to a narrower aspect of the invention, a circuit arrangement for an oscillator which can oscillate on any of a wide range of frequencies comprises an oscillator and a frequency discriminator or counting arrangement adapted to produce a direct current voltage in the output thereof depending upon the frequency of the input fed to the said discriminator or counting arrangement, and means for feeding said output voltage to said oscillator to maintain the frequency generated by the latter.

According to another narrower aspect of the invention, a circuit arrangement for the stabilisation of an oscillator at any frequency to which it is set comprises a frequency discriminator or counting arrangement fed from the oscillator and adapted to produce a direct current voltage in the output thereof depending upon the frequency of the input and means for feeding said output direct current voltage to said oscillator in such manner that the value of said output voltage maintains the frequency of said oscillator, the said oscillator and discriminator being so chosen that their characteristics showing the relationship between frequency and controlling voltage or frequency and output voltage respectively, are substantially linear, and have equal slopes, in the vicinity of the required stabilised frequencies.

The invention is particularly suitable for application to the oscillator of a superheterodyne radio receiver to supply the frequency changes of the oscillator where the received signal drifts in frequency so as to maintain the resulting intermediate frequency substantially constant.

According to a feature of the invention therefore, in a superheterodyne receiver arrangements are provided for eliminating the effect due to frequency drift of the received waves. These arrangements comprise a frequency discriminator or counting arrangement fed from the output of the intermediate frequency stage and adapted to produce a direct current voltage in the output thereof depending upon the input frequency, and means for feeding said output current voltage to said oscillator stabilised at any frequency to

which it is set, the value of said direct current voltage determining the rate of change of frequency of said oscillator and bringing the frequency thereof to such a value as to maintain said intermediate frequency constant.

In carrying out the invention the oscillator is such that it remains stable in frequency at any frequency to which it is set and within the bandwidth of the control circuits but is readily disturbed in frequency by application of an additional control voltage from an external source.

The invention will be better understood from the following description taken in conjunction with the accompanying drawing in which

Fig. 1 shows in block schematic a frequency control arrangement according to the invention applied to an oscillation generator;

Fig. 2 shows in block schematic the invention applied to another and preferred form of oscillation generator; and

Fig. 3 shows in block schematic the invention incorporated in a superheterodyne receiver.

Referring to Fig. 1, the oscillator O feeds a frequency discriminator D, which provides an input voltage to the frequency control tube FV, in turn coupled back to the oscillator O. The frequency control tube operates on well known principles, and may depend, for example, on the "Miller" effect. Now, it is arranged that for a given displacement in frequency of the oscillator O, the discriminator sensitivity is such that its change of output voltage is exactly that which is required to produce that same change in frequency by application of the voltage to the frequency control tube. If, now, the discriminator characteristic (input frequency versus output voltage) exactly matches the frequency control tube-oscillator characteristic, (input voltage to FV versus output frequency of O) the oscillator does not tend to drift from any frequency to which it has been set.

A small additional frequency control voltage, applied from some external source represented at CV will now cause the oscillator frequency to increase or decrease according to the sense of the control voltage.

In practice, the discriminator characteristic and the frequency control tube characteristic cannot be perfectly matched, so that the oscillator may have only one, or perhaps several, perfectly stable working positions on the characteristic. The tendency to drift towards its nearest stable frequency can, however, be made very small, and the rate of drift, depending also upon the time con-

stants in the discriminator and control circuits, may be adjusted at will.

A preferred form of this frequency-controlled source of oscillation is shown in Fig. 2.

The principle on which this oscillation generation arrangement operates is fully described in the specification of British application No. 5358/41 and the corresponding United States application No. 460,578, filed October 2, 1942.

A stable oscillator O of frequency F is connected directly to a modulator M₂, and via a phase controlling thermionic tube PC to modulator M₁, to which a frequency band of mean frequency f is also passed as hereafter explained. Filter F₁ selects from the output of M₁ a band of frequencies, of mean frequency $(F-f)$ (or $F+f$), which is passed to M₂.

The function of the delay network DL is to provide a linear phase shift of θ radians per Δ cycles change in the frequency f . If the frequency f changes to $f+\Delta$, the phase distortion produced by the delay network DL will be advanced by θ radians. Similarly any other frequency change between $+\Delta$ and $-\Delta$ will produce a corresponding phase shift between $+\theta$ and $-\theta$.

If the amplification around the circuit is sufficiently great, oscillations are set up, and these oscillations must be of mean frequency f , in order to pass through the filter F₂, and also of frequency $F \pm f$ to pass through the filter F₁. The delay network is designed to give a linear distortion over a frequency band of $f \pm \Delta$. If a certain frequency f is produced when the frequency F, applied to the modulator M₁, has a definite phase relationship to the output of the oscillator O applied to the modulator M₂, and if a change in phase relationship occurs, the correct phase relationship around the loop has now been upset and the frequency f will rise or fall to accommodate itself to the new conditions.

For instance, if the phase of the frequency F injected into the modulator M₁ is advanced by the phase control tube PC θ radians with respect to the same frequency F from the oscillator O directly injected into the modulator M₂, oscillations can only be maintained in the loop if the frequency f is increased to $f+\Delta$ and the frequency $F \pm f$ is increased to $F \pm (f+\Delta)$. Oscillations at these new frequencies are quite stable. Filter F₂ selects from the output of M₂ the frequency band of mean frequency f , which is passed to M₁. At some point in the loop path M₁—M₂—M₁ is inserted a delay network DL or alternatively the required delay may be produced in any of the components of the circuit, for instance, the filters.

The circuit as described up to this point produces oscillation of frequency f in the path M₂ to M₁, and oscillation of frequency $F-f$ or $F+f$ in the path M₁ to M₂. Now, as explained above and in the said specification of application 460,578, a phase shift produced by the phase control tube PC produces a corresponding change in the frequency f . The frequency f is now fed from filter F₂ to a discriminator D, or frequency counter, the output voltage of which is applied to the phase control tube PC and exactly matches the phase control voltage necessary to maintain the frequency applied to the discriminator. With the discriminator connected in this manner the frequency f will be held constant, since any change thereof will produce a voltage in the output of the discriminator D which will affect the

control tube PC so as to shift the frequency in the opposite direction.

If, now, the D. C. voltage from the discriminator D, as applied to the control tube PC, is supplemented by an additional D. C. frequency control voltage from an external source CV, the frequency of the oscillations speeds up or slows down, according to the sense of the control voltage, until the control voltage is removed.

10 The frequency for controlling the oscillation circuit may be obtained from the output of either filter. Likewise the output of either filter may be used for any desired purpose, for example, as the local oscillation of a superheterodyne receiver. As shown, the filter F₁ is shown with an output circuit for this purpose.

In either of the arrangements shown in Figs. 1 and 2 the source of control voltage CV may comprise a voltage generated in response to the deviation of the intermediate frequency from normal in a superheterodyne receiver. Such a receiver incorporating the invention is shown in Fig. 3. In Fig. 3, H.F. is the high frequency amplifier, FC the heterodyning stage, IFA the intermediate frequency amplifier and DET the low frequency detector stage. The oscillation generator is the same as that shown in Fig. 2 and like parts in both figures are given the same references. The stabilisation of the locally generated oscillation f at any frequency to which it is set is effected by the discriminator D and the voltage depending upon the frequency drift of the received frequency is generated by discriminator D₁. These two voltages are applied in series to the phase control tube PC. The time constant of the circuit between the discriminator D₁ and the frequency control tube PC is not fixed. In series with the automatic frequency control is introduced a four-element bridge rectifier R with capacity C across the line. A battery B is connected in series with the secondary winding of a transformer T, across the free corners of the bridge, in such sense that the four rectifier elements of the bridge are made non-conducting. In this condition, the time constant of RC circuit is infinity, or at least very large.

A portion of the output from the intermediate frequency amplifier IFA is now introduced to the other or primary winding of transformer T, and, if it is sufficient, overcomes the bias on the rectifiers due to the battery, and passes rectified current through the battery, and through the rectifiers. In this condition, the rectifier impedance may be reduced to a low value, the series impedance along the automatic frequency control line L is reduced, and the time constant of the line becomes short. This variable time constant feature forms the subject of my copending application Serial No. 449,293, filed July 1, 1942.

60 In the presence of a signal, the automatic control of frequency is operative and quick. If, now, the signal is interrupted, or quickly fades, the time constant of the RC circuit becomes very large, and the frequency control voltage across the condenser C is maintained.

The two discriminator voltages are connected in series-aiding before application to the variable time constant circuit RC. The filter F₂ at frequency f is a band-pass filter covering the total range of frequency control required, and this filter itself provides the delay as stated in reference to Fig. 2.

Whilst a particular embodiment of the invention has been described by way of example, others

will occur to those skilled in the art and which fall within the scope of the appended claims.

What is claimed is:

1. A frequency stabilized oscillation generating system comprising a closed oscillating circuit, an oscillator, an oscillator output circuit, means for shifting the phase of the oscillator output in said output circuit, means for introducing said phase shifted output into the closed circuit, the closed circuit oscillating frequency being varied in proportion to said phase shift, and means for varying said phase shift in proportion to variations in frequency in the closed circuit and thereby stabilizing said frequency.

2. A system as set forth in claim 1, in which said closed circuit includes a first modulating means for introducing said phase-shifted output into the circuit, filter means for selecting from the first modulating means output a frequency combining the oscillator frequency and another frequency to which the oscillating circuit is tuned, a second modulating means for combining the filter output and the oscillator output, and delay means including a filter for supplying said other frequency from the second modulating means to the first modulating means.

3. A system as set forth in claim 1, in which the means for varying the phase shift comprises a discriminator connected between the closed circuit and phase shifting means.

4. In a superheterodyne receiving system which includes a heterodyning stage followed by an intermediate frequency amplifier, a frequency stabilized oscillation generating system comprising a closed oscillating circuit, an oscillator, an oscillator output circuit, means for shifting the

phase of the oscillator output in said output circuit, means for introducing said phase-shifted output into the closed circuit, the closed circuit frequency being varied in proportion to said phase shift, means for varying said phase shift in proportion to variations in frequency in the closed circuit and thereby stabilizing said frequency, and means for supplying oscillations from the closed circuit to the heterodyning stage.

10 5. A system as set forth in claim 4, including means for varying said phase shift in accordance with variations in the output frequency of the intermediate frequency amplifier and thereby compensating for said variations.

15 6. A system as set forth in claim 4, including discriminator means connected between the intermediate frequency amplifier output and the phase shifting means, arranged to correct variations in said amplifier output frequency by varying the closed circuit frequency through proportional changes in said phase shift.

7. A system as set forth in claim 4, including discriminator means connected to said amplifier output and means for continuing the application 25 of a regulating potential from the discriminator means to the phase shifting means after the signal producing said potential has failed, comprising a capacitance arranged in circuit between the discriminator means and the phase shifting 30 means to transmit to the latter a regulating potential from the discriminator means, and means in circuit between the condenser and the discriminator means actuated by failure of said signal to block discharge of the condenser toward 35 the discriminator means.
